UNITED STATES PATENT OFFICE.

GERHARDT G. M. F. HARTMANN, OF NEW YORK, N. Y.

DESIGN FOR A GEM-SETTING.

SPECIFICATION forming part of Design No. 33,769, dated December 25, 1900.

Application filed November 22, 1900. Serial No. 37,406. Term of patent 7 years.

To all whom it may concern:

Be it known that I, GERHARDT G. M. F. HARTMANN, a citizen of the United States, and a resident of the city of New York, borough 5 of Manhattan, in the county and State of New York, have invented and produced a new and original Design for a Gem-Setting, of which the following is a specification, reference being had to the accompanying drawings, forming 10 a part thereof, in which—

Figure 1 is a plan view of a gem-setting embodying the features of my design, and Fig. 2 is a side elevation of the same.

The leading features of the design consist 15 in a rectangular border A and chains of globular and irregular bead-like figures B within said border, arranged parallel with its sides, the bead-like figures extending beyond the upper edges of the border.

The minor features of the design consist in 20 the irregular formation of the outer chains of bead-like figures, such figures having facets, and in the globular form of the inner bead-like figures, which globular bead-like figures surround a central irregular figure. 25

Having thus described my invention, I claim as new and desire to secure by Letters Patent—

The design for a gem-setting herein shown and described. 30

In testimony whereof I have signed my name to this specification in the presence of two subscribing witnesses.

GERHARDT G. M. F. HARTMANN.
